UNITED STATES PATENT OFFICE.

RAYMOND P. LOUGHLIN, OF BROOKLYN, NEW YORK.

DRIFTING VALVE AND CONTROL MECHANISM.

Application filed October 20, 1924. Serial No. 744,689.

To all whom it may concern:

Be it known that I, RAYMOND P. LOUGHLIN, a citizen of the United States, residing at 480 East 15th Street, Brooklyn, in the county of Kings and State of New York, have invented certain new and useful Improvements in a Drifting Valve and Control Mechanism, of which the following is a specification.

10 My invention relates to a drifting valve and control mechanism and more particularly to a steam locomotive drifting valve and its novelty consists in the adaptation and arrangement of parts as will be more 15 fully hereinafter pointed out.

The use of superheated steam in locomotives necessitates frequent overhauling of the cylinders and valve chests in order to remove the large deposits of carbon 20 which have accumulated in the exhaust passageways and steam ports and upon the valves and pistons. The carbon, which is hard and difficult to remove, is the result of the carbonization of the cylinder lubricating oil when the locomotive is coasting 25 or drifting at which time air is drawn into the cylinders thru the relief valves or thru the exhaust passageway and smoke box. This air striking the films of oil which 30 are at the high temperature of the superheat causes them to disintegrate leaving a dense hard deposit of carbon which in a comparatively short time chokes up the ports and passage ways to such an extent 35 that satisfactory operation is impossible. Moreover, cinders from the smoke box or bits of the carbon will cause scoring of the rings and seats with consequent leakage and poor performance. Also if steam 40 is not supplied in some amount to the main cylinders under all running conditions the lubrication of the cylinders ceases with the resultant danger of overheating and scoring of the cylinders.

45 To overcome this carbonization various devices have been used to admit saturated steam from the boiler to some portion of the cylinder or valve chest, while the locomotive is drifting, but such devices are complicated and sometimes freeze up in very cold weather. My device overcomes all of 50 these difficulties and does so in an efficient and economical manner.

55 Referring to the accompanying drawings Figure 1 is an end elevation of the device as installed upon a locomotive. Figure 2

is a side elevation of the device showing the connections to the steam chests. Figure 3 is a plan of one of the connections to the control valve. Figure 4 is a vertical section of the control valve on the line 4-4 of Figure 1. Figure 5 is an end elevation of the control valve with the lower portion broken away and a vertical section on the line 5-5 of Figure 4. Figure 6 is a horizontal section on the line 6-6 of Figure 4. Figures 7 and 8 show in vertical section different positions of the inner parts of the control valve under different conditions. Figure 9 is a side elevation of the upper 70 portion of the control valve. Figures 10 and 11 are vertical sections on the lines 10-10 and 11-11 respectively of Figure 9. Figure 12 is a horizontal section on the line 12-12 of Figure 9. Figure 13 is a 75 vertical section on the line 13-13 of Figure 1. Figure 14 is a vertical section on the line 14-14 of Figure 13. Figure 15 is a plan view of a portion of the main valve. Figure 16 is a plan view of the main 80 valve with the top removed showing a quarter section thru one of the ports. Figure 17 is a plan view of one of the parts of the main valve.

In the drawings it will be seen that my 85 device consists of two major parts, an air operated steam valve 21, hereinafter called the main valve, for admitting saturated steam to the steam chests 22 thru pipes 23 and 24 and a steam operated air valve 25 90 for controlling the opening and closing of the main valve 21. As the locomotive is operated the main valve 21 must be closed when the throttle is open and also when the locomotive is standing still. It must be 95 open when the locomotive is drifting. The control valve 25 accomplishes this by admitting compressed air to line 26 and exhausting line 27, thereby closing the main valve 21, or vice versa, thereby opening the 100 main valve 21. The main valve 21 is mounted on the top of the boiler 28 and receives saturated steam from the steam dome 29 thru pipe 30. The control valve 25 mounted on the smoke box 31 receives 105 its supply of compressed air thru line 32 from the main air reservoir 33. The lower portion of the control valve is connected to the supply pipe 34 leading to the steam chest 22 by means of pipe 35. Figure 3 110 shows how line 27 branches so as to connect with arms 53 and 54 of the control

valve 25. Line 26 branches in a like manner.

As shown in Figure 4 the control valve 25 consists of a body 25^a in which slides 5 a sleeve 36 and a plunger 37. The lower end of the plunger is rigidly attached to a piston 38 which slides in a renewable bushing 42 driven into the lower end of the control valve body 25^a. This lower end is 10 closed by a cap 39 containing a passage 40 thru which steam can pass from the supply pipe 34 by way of line 35 and push up piston 38 which is made steam tight with rings 41. The lower end of the valve body 25 is covered 15 with asbestos 43 to prevent excessive condensation and the entire lower portion is protected from the elements by cover 44 held in place by nuts 45 which screw onto cap 39. To the upper end of the plunger 20 37 is attached a leather cup 46 fastened by nuts 47. This upper end of the plunger slides inside of sleeve 36 which has the upper inside portion enlarged to receive the leather cup 48 fastened by means of nuts 25 49 to the end of cap 50 which closes the top of the valve body 25^a. The space 48^a between the cups 46 and 48 is supplied with compressed air thru passage 51 in cap 50 connected by a pipe 52 to port 61 opening 30 into the upper valve chamber 32^b in arm 53; thus causing both the plunger 37 and the sleeve 36 to be forced continually downward.

The opposite sides of the sleeve 36 are 35 formed with indented portions 36^a and 36^b having inclined sides which as the sleeve moves up or down make four tappets 55, which are horizontally mounted in valve body 25^a, move in or out. These tappets 55 40 slide in bushings 56 driven into the arms 53 and 54 of the valve body 25^a. Any movement of the tappets 55 is transmitted to four poppet valves 57 which are pressed 45 on their seats by springs 58. The valves in arm 53 have on their ends leather cups 59 held in place by washers 60 adapted to make the ends of said valves air tight. In the right hand arm 53 the valve chambers are supplied with compressed air thru line 50 32 screwed into opening 62 which leads to the valve chamber 32^a in the lower part of arm 53 as shown in Figure 12. An upper valve chamber 32^b communicates with the lower thru opening 63 as shown in Figure 55. The indented portions 36^a and 36^b on sleeve 36 are so arranged that when the upper right valve 57 is shut the upper left is open, the lower right open and the lower left closed, or vice versa. Caps 53^a screwed 60 into arm 53 close the valve chambers 32^a and 32^b. There are similar caps 54^a in arm 54.

In the lower portion of the valve body 25^a are driven two pins 65 and 74 which 65 serve as pivots for two pawls 64 and 73 respectively. Pawl 64 is pressed against

sleeve 36 by a tappet 66 and a spring 67, and pawl 73 in a similar manner by a tappet 75 and a spring 76. Caps 68 close the openings which contain these tappets and springs. Pawl 64 has two shoulders 69 and 72, and pawl 73 has a shoulder 77, all three of which are adapted to engage the lower surface 36^c of sleeve 36 and to detain the sleeve in three different positions as may be observed more clearly in Figure 7. 76 Attached rigidly to piston 38 is a striking piece 71 having a surface 70 adapted to engage shoulder 72 on pawl 64 and on the downward stroke of the piston 38 to throw pawl 64 far enough out to disengage shoulder 69 from the sleeve 36, but not far enough to prevent shoulder 72 from engaging the sleeve when at the lowest position as shown in Figure 8. On pawl 73 just below shoulder 77 is a surface 78 adapted to be 80 engaged by the upper corner of striking piece 71 on the upward stroke of piston 38, whereby the pawl 73 can be thrown out and shoulder 77 disengaged from the sleeve 36. 85

The sleeve 36 has three positions corresponding to the position of the main valve 21 when the locomotive is in active service. Figure 4 shows the positions of the internal parts of the control valve 25 when the locomotive is running under power. Figure 7 90 shows the positions when drifting. Figure 8 shows them when standing still. Figure 13 shows the position of main valve 21 when running or standing. When drifting the main valve 21 is open.

In Figure 12 a feather key 81 keeps sleeve 36 in proper alignment with respect to tappets 55. Passage 79 is the exhaust port for the branch of line 26 which enters arm 54 and passage 80 is the inlet port for 105 the branch of line 26 which enters arm 53. There are similar ports 79^a and 80^a for line 27 as shown in Figure 9.

The main valve 21 as shown in Figure 13 has an upper portion 21^a having two cylinders 82 closed by caps 83. A piston 84 with heads 85, leather cups 86, washers 87 and nuts 88 slides in cylinders 82. Compressed air entering a port 89 thru line 27 will cause the piston 84 to move to the right, 110 or if entering a port 90 thru line 26 then to the left. This motion is transmitted to arm 91 clamped to piston rod 84 by means of bolt 92 as will be evident from Figure 14. In the end of arm 91 is driven a pin 115 93 upon which flanged roller 94 can turn freely. The rectilinear motion of the roller is transmitted to a revolvable stem 95 by means of lever 96 clamped to stem 95 by means of bolt 97 as shown in Figure 15. 120 The lower end of stem 95 has a tongue 98 which fits into groove 99 in the top of the valve plug 100. This plug 100 is hollow and has two ports 100^a which when aligned 125 with ports in the base 21^b of the main valve 130

21 allows steam to flow thru lines 23 and 24 to the steam chests 22 as shown in Figure 1. Referring to Figure 13 chamber 104 in the base of the main valve 21 is always full of 5 saturated steam supplied from the dome thru line 30. The plug 100 is tapered and held firmly on a renewable seat 101 by the pressure of steam admitted to an upper chamber 102 thru passage 103. Collar 95^a 10 on stem 95 prevents escape of steam between stem 95 and a renewable bushing 105. Referring to Figure 14 the arm 91 has an extension 106 which bears against cross bar 107 which joins the cylinders 82 and in 15 junction with finger 108 keeps arm 91 in proper alignment with respect to lever 96. Both the extension 106 and the finger 108 serve as stops for piston 84 by striking against end surfaces 110 of the cylinders 82 20 as piston 84 moves back and forth.

Figure 17 shows the plan of lever 91 with flat sides 109 which stop against end surfaces 110 of the cylinders 82.

Figure 13 shows the position of the piston 25 84 when the main valve 21 is closed, line 27 being exhausted and line 26 filled with air. Figure 16 shows the position of the plug 100 when the main valve 21 is closed. Figure 14 shows the position of the plug 100 when 30 the main valve 21 is open at which time line 26 is exhausted and line 27 filled with air.

The operation of my device is as follows. When the locomotive throttle is opened 35 steam enters the supply pipe 34 from the superheater manifold making the locomotive move in the usual and well known manner. A small portion of the steam entering thru line 35 forces piston 38 to rise striking sleeve 36 and forcing it to move to 40 the extreme position shown in Figure 4. Pawl 64 pivoted on pin 65 then slips into the position shown under the influence of tappet 66 and spring 67. As long as the throttle is open piston 38 or shoulder 69 on 45 pawl 64 will hold sleeve 36 in running position. The sleeve in turn holds the upper left valve 57 open and permits the upper right valve 57 to close thereby exhausting line 27. At the same time it opens the lower 50 right valve 57 and closes the lower left valve 57 thereby filling line 26 with compressed air. This closes the main valve 21. When the throttle is closed and the locomotive begins to drift line 35 exhausts thru the stack, 55 and piston 38 returns to its lowest position under the influence of the compressed air acting on cup 46. In doing so surface 70 of striking piece 71 attached rigidly to piston 38 hits shoulder 72 on pawl 64 causing 60 it to release the sleeve 36 which is then forced down under the influence of the compressed air in chamber 48^a immediately above cup 46. Pawl 73 pivoted on pin 74 has in the meantime moved into position 65 under the influence of tappet 75 and spring 76 and holds the sleeve 36 in the drifting position when the lower surface 36^c of the sleeve 36 strikes the shoulder 77 on the pawl 73 as shown in Figure 7. The upper left and lower right valves 57 are now closed 75 and upper right and lower left valves 57 are now open thereby causing line 26 to exhaust and line 27 to fill with compressed air and causing the main valve 21 to open and allow saturated steam to flow into the steam 80 chests 22 thru lines 23 and 24. The size of the pipes in lines 23 and 24 are such that the pumping action of the main engines is sufficient to keep the pressure in the steam chests 22 from building up to a point which would 85 overcome the force of the air pressure on piston 38 and make it rise. When the brakes are applied and the locomotive gradually comes to a stop, the pumping action of the engines gradually diminishes and the steam pressure in the valve chest and line 35 builds up until it is sufficient to push piston 38 upward until the upper corner of the striking piece 71 strikes surface 78 on pawl 74 thereby 90 throwing the pawl 74 out and allowing sleeve 36 to descend and rest on the shoulder 72 of pawl 64 as shown in Figure 8. The upper right and the lower left poppet valves 57 will now be closed and the lower right and upper left valves 57 will be open causing line 27 to exhaust and line 26 to fill with compressed air thereby closing the main 95 valve 21.

Should the throttle be opened again while drifting and before the pressure has built up in the manner just described, sleeve 36 will be pushed again to the upper or running position by piston 38 thereby closing the main valve 21.

While I have shown and described various 100 ways and forms in which my invention may be carried out, I wish it to be understood that I am not limited thereto but that my invention may be embodied in numerous 105 modifications without any departure from the spirit and scope thereof.

I claim:

1. In combination with a steam reciprocating locomotive, means for conveying an auxiliary supply of steam from the boiler of the locomotive to the main engines of the locomotive, valve means for controlling said auxiliary supply of steam, an oscillatable member actuated by the normal operation of the locomotive, means actuated by the normal operation of the locomotive for retaining said member at one extremity of its path while the locomotive is standing, at the other extremity of its path while the locomotive is running under power, and at 115 an intermediate position while the locomotive is drifting, and means connecting said oscillatable member and said valve means whereby the closing of said valve means is 120 effected by the movement of said member to 125

- either extremity of its path and the opening of said valve means is effected by the movement of said member to said intermediate position.
5. In combination with a steam reciprocating locomotive, means for conveying an auxiliary supply of steam from the boiler of the locomotive to the main engines of the locomotive, valve means for controlling said auxiliary supply of steam, an oscillatable member adapted to be detained in a position intermediate with respect to the extremities of the path of said oscillatable member, means actuated by the normal operation of the locomotive for oscillating said member in one direction when the locomotive is running under power and in the opposite direction when the locomotive ceases to run under power, means actuated by the normal operation of the locomotive for detaining said member in said intermediate position on the back movement of said member, means actuated by variation of the locomotive steam chest pressure for interrupting said detaining means, and means connecting said oscillatable member and said valve means whereby the closing of said valve means is effected by the movement of said member to either of its extreme positions and whereby the opening of said valve means is effected by the movement of said member to said intermediate position.
6. In combination with a steam reciprocating locomotive, means for conveying an auxiliary supply of steam from the boiler of the locomotive to the main engines of the locomotive, valve means for controlling said auxiliary supply of steam, an oscillatable member adapted to be detained in a position intermediate the extremities of the path of the oscillatable member, means actuated by variation of the locomotive steam chest pressure for oscillating said member in one direction when the locomotive is running under power and in the opposite direction when the locomotive ceases to run under power, means actuated by variation of the locomotive steam chest pressure for detaining said member in said intermediate position on the back movement of said member, means actuated by variation of the locomotive steam chest pressure for restraining said member from assuming said intermediate position when the locomotive ceases to run under power, means actuated by variation of the locomotive steam chest pressure for interrupting said restraining means and said detaining means, and means connecting said oscillatable member and said valve means whereby the closing of said valve means is effected by the movement of said member to either of its extreme positions and whereby the opening of said valve means is effected by the movement of said member to said intermediate position.
7. In combination with a steam reciprocating locomotive, means for conveying an auxiliary supply of steam from the boiler of the locomotive to the main engines of the locomotive, valve means for controlling said auxiliary supply of steam adapted for air operation, an oscillatable member adapted to be detained in a position intermediate the extreme positions of said member, means actuated by variation of the locomotive steam chest pressure for oscillating said member in one direction when the locomotive is running under power and in the opposite direction when the locomotive ceases to run under power, means actuated by variation of the locomotive steam chest pressure for detaining said member in said intermediate position on the back movement of said member, means actuated by variation of the locomotive steam chest pressure for restraining said member from assuming said intermediate position when the locomotive ceases to run under power, means actuated by variation of the locomotive steam chest pressure for interrupting said restraining means and said detaining means, means connecting said oscillatable member and said valve means whereby the closing of said valve means is effected by the movement of said member to either of its extreme positions and the opening of said valve means is effected by the movement of said member to said intermediate position.
8. In combination with a steam reciprocating locomotive, means for conveying an auxiliary supply of steam from the boiler of the locomotive to the main engines of the locomotive, valve means for controlling said auxiliary supply of steam adapted for air operation, an oscillatable member adapted to be detained in a position intermediate the extreme positions of said member, means actuated by variation of the locomotive steam chest pressure for oscillating said member in one direction when the locomotive is running under power and in the opposite direction when the locomotive ceases to run under power, means actuated by variation of the locomotive steam chest pressure for detaining said member in said intermediate position on the back movement of said member, means actuated by variation of the locomotive steam chest pressure for restraining said member from assuming said intermediate position when the locomotive ceases to run under power, means actuated by variation of the locomotive steam chest pressure for interrupting said restraining means and said detaining means, means connecting said oscillatable member and said valve means whereby the closing of said valve means is effected by the movement of said member to either of its extreme positions and the opening of said valve means is effected by the movement of said member to said intermediate position.

6. In combination with a steam reciprocating locomotive, means for conveying an auxiliary supply of steam from the boiler of the locomotive to the main engines of the locomotive, valve means for controlling said auxiliary supply of steam adapted for air operation, an oscillatable member adapted to be detained in a position intermediate the extreme positions of said member, means actuated by variation of the locomotive steam chest pressure for oscillating said member in one direction when the locomotive is running under power and in the opposite direction when the locomotive ceases to run under power, means actuated by variation of the locomotive steam chest pressure for detaining said member in said intermediate position on the back movement of said member, means actuated by variation of the locomotive steam chest pressure for restraining said member from assuming said intermediate position when the locomotive ceases to run under power, means actuated by variation of the locomotive steam chest pressure for interrupting said restraining means and said detaining means, means connecting said oscillatable member and said valve means by an air supply to the valve means, and secondary valve means comprising poppet valves actuated in pairs by the oscillatable member for controlling said air supply whereby the closing of said valve means is effected by the movement of said member to either of its extreme positions and whereby the opening of said valve means is effected by the movement of said member to said intermediate position. 70 75
8. In combination with a steam reciprocating locomotive, means for conveying an auxiliary supply of steam from the boiler of the locomotive to the main engines of the locomotive, valve means for controlling said auxiliary supply of steam, an oscillatable member adapted to be detained in a position intermediate the extreme positions of said member, means actuated by variation of the locomotive steam chest pressure for oscillating said member in one direction when the locomotive is running under power and in the opposite direction when the locomotive ceases to run under power, means actuated by variation of the locomotive steam chest pressure for detaining said member in said intermediate position on the back movement of said member and means actuated by variation of the locomotive steam chest pressure for restraining said member from assuming said intermediate position when the locomotive ceases to run under power comprising pawls under continual spring pressure against said member, means actuated by variation of the locomotive steam chest pressure for interrupting said restraining means and said detaining means, and means connecting said oscillatable member and said valve means whereby the closing of said valve means is effected by the movement of said member to either of its extreme positions and whereby the opening of said valve means is effected by the movement of said member to said intermediate position. 80 85 90 95 100
7. In combination with a steam reciprocating locomotive, means for conveying an auxiliary supply of steam from the boiler of the locomotive to the main engines of the locomotive, valve means for controlling said auxiliary supply of steam adapted for air operation, an oscillatable member adapted to be detained in a position intermediate the extreme positions of said member, means actuated by variation of the locomotive steam chest pressure for oscillating said member in one direction when the locomotive is running under power and in the opposite direction when the locomotive ceases to run under power, means actuated by variation of the locomotive steam chest pressure for detaining said member in said intermediate position on the back movement of said member, means actuated by variation of the locomotive steam chest pressure for restraining said member from assuming said intermediate position when the locomotive ceases to run under power, means actuated by variation of the locomotive steam chest pressure for interrupting said restraining means and said detaining means, means connecting said oscillatable member and said valve means by an air supply to the valve means, secondary 105 110 115 120 125 130

said member from assuming said intermediate position when the locomotive ceases to run under power comprising pawls under continual spring pressure against said member, means actuated by variation of the locomotive steam chest pressure for interrupting said restraining means and said detaining means comprising a plunger having striker means adapted to engage a cam surface on each of said pawls, and means connecting said oscillatable member and said valve means whereby the closing of said valve means is effected by the movement of said member to either of its extreme positions and whereby the opening of said valve means is effected by the movement of said member to said intermediate position.

10. In combination with a steam reciprocating locomotive, means for conveying an auxiliary supply of steam from the boiler of the locomotive to the main engines of the locomotive, valve means for controlling said auxiliary supply of steam, an oscillatable member adapted to be detained in a position intermediate the extreme positions of said member, means actuated by variation of the locomotive steam chest pressure for oscillating said member in one direction when the locomotive is running under power and in the opposite direction when the locomotive ceases to run under power comprising a plunger subject to upward steam chest pressure of said locomotive and adapted to push said member, said plunger and said member being subject to continual downward resilient means, means actuated by variation of the locomotive steam chest pressure for detaining said member in said intermediate position on the back movement of said member, means actuated by variation of the locomotive steam chest pressure for restraining said member from assuming said intermediate position when the locomotive ceases to run under power, means actuated by variation of the locomotive steam chest pressure for interrupting said restraining means and said detaining means, and means connecting said oscillatable member and said valve means whereby the closing of said valve means is effected by the movement of said member to either of its extreme positions and whereby the opening of said valve means is effected by the movement of said member to said intermediate position.

15. In combination with a steam reciprocating locomotive, means for conveying an auxiliary supply of steam from the boiler of the locomotive to the main engines of the locomotive, valve means for controlling said auxiliary supply of steam, an oscillatable sleeve adapted to be detained in a position intermediate the extreme positions of said sleeve, means actuated by variation of the locomotive steam chest pressure for oscillating said sleeve in one direction when the

locomotive is running under power and in the opposite direction when the locomotive ceases to run under power comprising a plunger subject to upward steam chest pressure of said locomotive and adapted to push said sleeve, said plunger and said sleeve being subject to continual downward compressed air pressure, means for supplying said compressed air pressure, means actuated by variation of the locomotive steam chest pressure for detaining said sleeve in said intermediate position on the back movement of said sleeve, means actuated by variation of the locomotive steam chest pressure for restraining said sleeve from assuming said intermediate position when the locomotive ceases to run under power, means actuated by variation of the locomotive steam chest pressure for interrupting said restraining means and said detaining means, and means connecting said oscillatable sleeve and said valve means whereby the closing of said valve means is effected by the movement of said sleeve to either of its extreme positions and whereby the opening of said valve means is effected by the movement of said sleeve to said intermediate position.

20. In combination with a steam reciprocating locomotive, means for conveying an auxiliary supply of steam from the boiler of the locomotive to the main engines of the locomotive, valve means for controlling said auxiliary supply of steam, said means for conveying an auxiliary supply of steam comprising a pipe line from the steam dome of the locomotive to the valve means and a pipe line from the valve means to each steam chest of the locomotive, an oscillatable member adapted to be detained in a position intermediate the extreme positions of said member, means actuated by variation of the locomotive steam chest pressure for oscillating said member in one direction when the locomotive is running under power and in the opposite direction when the locomotive ceases to run under power, means actuated by variation of the locomotive steam chest pressure for detaining said member in said intermediate position on the back movement of said member, means actuated by variation of the locomotive steam chest pressure for restraining said member from assuming said intermediate position when the locomotive ceases to run under power, means actuated by variation of the locomotive steam chest pressure for interrupting said restraining means and said detaining means, and means connecting said oscillatable member and said valve means whereby the closing of said valve means is effected by the movement of said member to either of its extreme positions and whereby the opening of said valve means is effected by the movement of said member to said intermediate position.

In testimony whereof I affix my signature.
RAYMOND P. LOUGHLIN,
